BATHING GARMENT

Charles N. Winship, Wakefield, Mass.

Application March 5, 1932. Serial No. 596,916

3 Claims. (Cl. 2—67)

This invention relates to bathing suits, bathing trunks, and other short legged garments.

It aims to improve garments of this type with a view to producing a more comfortable and better fitting article.

The nature of the invention will be readily understood from the following description when read in connection with the accompanying drawing, and the novel features will be particularly pointed out in the appended claims.

In the drawing,

Figure 1 is a front elevation of a garment embodying this invention;

Fig. 2 is a crotch view of the garment shown 15 in Fig. 1;

Fig. 3 is a plan view of the inside crotch portion of the garment;

Figs. 4 and 5 are plan views of the front and rear sections of the garment; and

20 Figs. 6 and 7 are plan views of the inner and outer crotch pieces of the garment.

In bathing suits and other short legged garments, particularly those of the athletic type, it is the usual practice to insert a diamond-shaped 25 gusset in the crotch to give the added fullness required at this point. The corners connected by the longest dimension of this piece are located at the front and rear, respectively, of the garment, and the other two corners are joined to the 30 legs at opposite sides of the crotch and directly between the legs. In a garment made of heavy fabrics, such as those used in bathing suits, this construction produces a bunching of the material where the seams meet between the legs 35 and at opposite sides of the crotch. Such bunching frequently causes severe chafing. To avoid this difficulty and to improve the fit of garments of this type constitutes the chief object of this invention.

40 The bathing suit shown in Fig. 1 includes a shirt portion 2 stitched at 3 to a pair of trunks 4, the trunks including short legs 5—5. Connecting these legs is a crotch piece 6 joined to the front and rear portions of the trunk 4 by front 45 and rear seams 7 and 8, respectively, which, instead of being located in the crotch, are positioned at the front and rear of the crotch. Preferably the opposite edge portions or margins of the crotch piece which extend from the front 50 toward the rear of the garment, form portions of the legs of the garment so that the seams 7 and 8 extend laterally entirely across the crotch from one leg to the other. They are spaced apart from front to rear by substantial distances so 55 that no seams are present in the crotch except

the seams 5' which are formed in hemming the legs and which completely surround the leg openings.

The trunks 4 may be made in several ways, in all of which the crotch piece 6 can be used substantially as shown. In a typical construction front and rear panels 9 and 10, respectively, are cut from suitable fabric, each of these sections having a central crotch notch, as indicated at 11 and 12, respectively. A crotch piece 6 of approximately the form shown in Fig. 7 is cut out of similar material, this piece being notched at opposite ends, as clearly shown in said figure. The central length of this crotch section is shorter than the lengths of the edges. One of the notched 60 ends is made substantially the length of the notch 11 in the front section 9, while the opposite notched end is made somewhat longer and of a length approximately equal to that of the notch 12 in the rear or back section 10. The opposite 65 notched ends of the crotch piece are stitched to the edges of the notches 11 and 12, respectively, thus forming the seams 7 and 8 previously referred to, and the margin of the leg portions are turned over and hemmed to form the seams 5'. 70 The top also may be hemmed if desired. 75

In many garments it is preferable to make the crotch piece double, in which case an inner piece 6', Fig. 6, of the same length as the part 6, but narrower than the latter, is cut out and is stitched 80 to the sections 9 and 10, together with the main crotch section 6. This inner or lining section of the crotch piece is shown in Fig. 3 at 6'. 85

The construction above described completely 90 avoids the bunching of seams between the legs and at opposite sides of the crotch which has been objectionable in prior garments because of its liability to produce chafing. In addition, it provides a garment which conforms more accurately to the shape of the wearer. It will be evident, 95 however, that the trunks may be made in ways other than that above described. For example, it may have front and rear median seams connecting two lateral sections which are approximately duplicates, or the entire body portion of the 100 trunks may be made of seamless knit tubing so that it will be substantially devoid of vertical seams in the body portion thereof.

Having thus described my invention, what I 105 desire to claim as new is:

1. A short legged garment comprising front and rear portions to protect the lower part of the trunk of the wearer's body, and a crotch piece joined to said portions and forming the crotch and parts of the legs of the garment, said crotch 110

piece having its front and rear ends notched, and said front and rear portions having central notches to which the notched ends, respectively, of said crotch piece are sewed, whereby the seams at said ends extend laterally of the garment from one leg to the other and are spaced one in front of the other.

2. A short legged garment comprising front and rear portions to protect the lower part of the 10 trunk of the wearer's body, and a crotch piece joined to said portions and forming the crotch and parts of the legs of the garment, said crotch piece having its front and rear ends notched, and said front and rear portions having central 15 notches to which the notched ends, respectively, of said crotch piece are sewed, the lateral edges of said crotch piece being hemmed where it part-

ly bounds the leg openings, and the seams at the ends of the crotch piece extending directly across the garment from one leg opening to the other.

3. A short legged garment comprising front and rear portions to protect the lower part of the 80 trunk of the wearer's body, said portions having central notches located at the front and rear, respectively, of the crotch, and a crotch piece having front and rear notched ends sewed to the 85 edges of said front and rear notches, respectively, the crotch piece extending laterally of the garment from one leg opening to the other, whereby the seams joining said crotch piece to the main body of the garment extend laterally of the garment at the front and rear, respectively, of the 90 crotch.
